United States Patent Office.

JONATHAN CRABTREE, OF PHILADELPHIA, PENNSYLVANIA, ASSIGNOR
TO JAMES BROMLEY & BROTHERS, OF SAME PLACE.

Design No. 3,718, dated October 19, 1869.

DESIGN FOR A CARPET-PATTERN.

The Schedule referred to in these Letters Patent and making part of the same.

I, JONATHAN CRABTREE, (assignor to the firm of JAMES BROMLEY & BROTHERS,) of Philadelphia, county of Philadelphia, State of Pennsylvania, have invented a Design for a Carpet-Pattern, of which the following is a specification.

The figure in the accompanying drawing represents sufficient of a carpet to illustrate my design, the remainder of the pattern being a repetition of that which is shown.

The design consists of the main figures A A and B B, with the intervening ornamentation.

Each of the figures A has a foliated border, *a*, of the character clearly shown in the drawing, and in each figure is a central sprig, *b*, between which and the border is a number of dots, *c*.

The figures A meet or nearly meet the points or angles of the square or diamond-shaped figures B, each of the latter having a border composed of par-

lel ribs, *e e e*, &c., ornamented as shown, and within this border a square or diamond-shaped ornament, *f*.

The space between the figures A A and B B is occupied by a series of ribs and foliated ornaments, *h*, parallel with the sides of the figures B, and by rows of spots and zigzag lines, *k*.

Irrespective of the colors employed,

I claim the design for a carpet-pattern, substantially as described, and as represented in and by the accompanying drawing.

In testimony whereof, I have signed my name to this specification, in the presence of two subscribing witnesses.

JONATHAN CRABTREE.
